UNITED STATES PATENT OFFICE.

MARIUS LATOUR, OF PARIS, FRANCE, ASSIGNOR TO LATOUR CORPORATION, OF JERSEY CITY, NEW JERSEY, A CORPORATION OF DELAWARE.

AERIAL FOR WIRELESS TELEGRAPHY AND TELEPHONY PURPOSES.

Application filed July 15, 1920, Serial No. 396,501, and in France October 18, 1917.

(GRANTED UNDER THE PROVISIONS OF THE ACT OF MARCH 3, 1921, 41 STAT. L., 1313.)

The invention relates to improvements in aerials for electro-magnetic wave reception and transmission purposes.

It has already been suggested in the mounting of an aerial for wireless telegraphy purposes, to utilize several earth plates mounted in parallel. The effect sought after by this arrangement is to reduce the ohmic losses in the soil.

Actually however it happens that the aerial current does not divide itself among the various earth plates so as to present a minimum loss so that any appreciable reduction of the losses in the ground is not generally found with such an arrangement.

The object of this invention is to ensure a distribution of the aerial current between the different earth plates, according to any proportions considered suitable for obtaining the smallest ohmic losses in the soil.

The invention is more particularly described with reference to the accompanying drawings in which:—

Figures 1 to 7 show various modifications of the invention.

Fig. 1 is a diagram of the ordinary arrangement of aerial. A source of high frequency 1, which is assumed to be the secondary of an air or iron cored transformer, feeds by the vertical lead wire 2, a series of conductors 3, and is connected on the other hand to an earth plate 4.

According to Fig. 2, in which the same figures indicate the same parts, it is proposed to divide the aerial current between two distinct earth plates 4 and 5 in any proportions considered suitable. In order to obtain this result, a coil 7 having two windings is provided, mounted magnetically in opposition. The aerial current then tends to be distributed between the earth plates 4 and 5 in such a way that the ampere windings of both coils counter-balance one another and that there is no magnetic flux resulting in the coil. In the case where equality of the currents in the earth plates is desired, the coil has two windings having a practically equal number of spirals. The coil 7 may have an iron core so as to be less bulky.

If it be assumed as in the case of Fig. 3, that three earth plates 4, 5, and 6 are avail-

able, two coils 7 and 8 are used. The division of the current between the earth plates 5 and 6 is ensured by the coil 8 and the division of the current between the plates 5 and 6 on the one hand and the plate 4 on the other, is ensured by the coil 7 as before.

In the case of Fig. 4, where the aerial normally comprises a self induction coil 7 intended to increase the wave length of the antenna, the various earth plates are connected at various suitable points on the self induction coil 7 so that the aerial current is divided in given proportions between the different earth plates.

Finally as shown in Fig. 5, distinct self-induction coils 7, 8, and 9 may be arranged on different earth plates.

It may appear advantageous as shown in Fig. 6 to only give to these distinct self-induction coils 7, 8 and 9, the value necessary for guaranteeing a certain distribution of the aerial current and to retain a common aerial inductance coil 7' to give the aerial the wave length corresponding to the frequency of the source 1, which inductance will be arranged on the other side of this source. In this way the difference of potential between the earth and the source 1 is reduced.

Instead of self inductance coils, in case it is desired to shorten the length of the aerial, it is advisable to provide capacities 10, 11, 12, as shown in Fig. 7.

It must be observed that all the arrangements described are applicable equally well to receiving as well as to transmitting aerials.

Claims:

1. The combination with an antenna structure, of a plurality of ground connections of unequal impedance, and impedance means for causing predetermined currents to flow in said ground connections, whereby the losses in said ground connections are minimized.

2. The combination with an antenna circuit comprising a plurality of ground connections of coupling means between said ground connections for effecting predetermined current flow in said connections.

3. The combination with an antenna cir-

cuit comprising a plurality of ground connections of a device associated with each of said ground connections, said devices being electrically coupled for effecting a predetermined current flow in said ground connections.

4. The combination with an antenna circuit comprising a plurality of ground connections, of a coil associated with each of said ground connections, said coils being electromagnetically coupled for effecting a predetermined current flow in said ground connections.

5. In combination, an antenna, a plurality of ground connections for said antenna,

means for coupling one of said ground connections to the remainder of said ground connections, and means for coupling each of said remaining ground connections together.

20

6. In an antenna system, a horizontal conductor, a lead wire to ground, ground plates spaced at unequal distances from the foot of said lead wire, a plurality of connections from said lead wire to said ground plates, and an impedance in each connection whereby predetermined currents flow through said connections.
